US0D1021108S

(12) **United States Design Patent** (10) Patent No.: **US D1,021,108 S**
(45) Date of Patent: ** Apr. 2, 2024

(54) **TOE SPLINT**

(71) Applicant: **Xiujun Xu**, Guangzhou (CN)

(72) Inventor: **Xiujun Xu**, Guangzhou (CN)

(73) Assignee: **Xiujun Xu**, Guangzhou (CN)

(**) Term: **15 Years**

(21) Appl. No.: **29/910,728**

(22) Filed: **Aug. 23, 2023**

(30) **Foreign Application Priority Data**

Jul. 5, 2023 (CN) 202330418598.6

(51) **LOC (14) Cl.** **24-02**

(52) **U.S. Cl.**

USPC **D24/192**
